(57) **CLAIM**

I claim the ornamental design for a stool with cover, as shown and described.

DESCRIPTION

FIG. 1 is a top, front, right perspective view of a stool with cover of the claimed design;

FIG. 2 is a front elevation view of the stool with cover shown in FIG. 1;

FIG. 3 is a rear elevation view of the stool with cover shown in FIG. 1;

FIG. 4 is a right elevation view of the stool with cover shown in FIG. 1;

FIG. 5 is a left elevation view of the stool with cover shown in FIG. 1;

FIG. 6 is a top plan view of the stool with cover shown in FIG. 1;

FIG. 7 is a bottom plan view of the stool with cover shown in FIG. 1;

FIG. 8 is a top front, right perspective view of the stool with cover shown in FIG. 1, in an alternate position with a top portion partially removed from a bottom portion;

FIG. 9 is a top, front, right perspective view of the stool with cover shown in FIG. 1, in an alternate position with the top portion fully removed from the bottom portion;

FIG. 10 is a top, front, right perspective view of the stool with cover shown in FIG. 1, in an alternate position with the top portion fully removed from the bottom portion;

FIG. 11 is a front elevation view of the bottom portion of the stool with cover shown in FIG. 1;

FIG. 12 is a rear elevation view of the bottom portion of the stool with cover shown in FIG. 1;

FIG. 13 is a right elevation view of the bottom portion of the stool with cover shown in FIG. 1;

FIG. 14 is a left elevation view of the bottom portion of the stool with cover shown in FIG. 1;

FIG. 15 is a top plan view of the bottom portion of the stool with cover shown in FIG. 1;

FIG. 16 is a bottom plan view of the bottom portion of the stool with cover shown in FIG. 1; and,

FIG. 17 is a top, front, right perspective view of the bottom portion of the stool with cover shown in FIG. 1.
